Attorney

UNITED STATES PATENT OFFICE.

LUIGI EMANUELI, OF MILAN, ITALY, ASSIGNOR TO PIRELLI & C., OF MILAN, ITALY.
A FIRM.

HIGH-TENSION ELECTRIC CABLE.

Application filed April 26, 1926, Serial No. 104,722, and in Italy May 16, 1925.

The high tension electric cables now in use generally consist of one or more conductors insulated with paper or textile material which has been saturated with oil and covered with a lead sheath.

There are particular types of cables that contain a cavity on the inside of the conductors, or between the conductor and insulation, which cavity remains filled with oil.

10 The electric lines or systems in which such cables are installed are then furnished with elevated containers also filled with oil and communicating with the cavity of the cable, thereby keeping the insulation always perfectly saturated even when, at low temperature, the oil contracts and forms, in the dielectric, empty spaces—that is, points of easy perforation.

15 The above mentioned cavity situated inside the conductor causes difficulty in the construction of the joints and other accessories (terminal boxes, oil reservoirs, etc.) rendering them complicated and costly. Moreover, the cavity happens to be located 20 where the electric stress is greatest, whereas the oil itself has a dielectric strength less than that of saturated paper.

25 The present invention refers to a type of cable particularly suitable for saturation with light oils and for systems furnished with oil feeding reservoirs in which the above mentioned difficulties are mostly eliminated or greatly reduced by the utilization of the cavity situated between the insulation 30 and the lead sheath, that is, where the electric stress has a lower value.

35 In the accompanying drawing, the single figure is a cross-section of a cable embodying the preferred structural features of the invention and including, in this instance, three conductors, though it is to be understood that no limitation to that particular number is contemplated.

40 According to the illustrated embodiment, 45 1 indicates the three conductors mentioned above, these conductors being provided each with a covering or wrapping 2 of oil-saturated paper or textile material and being suitably tied or bound together. The unit 50 thus formed as a covering layer 7 of insulation wrapped or wound around it, over which, in turn, a lead sheath 5 is fitted, and it is this sheath 5 which presents the most important features of my invention.

55 As will be seen in the drawing, the inner

surface of the sheath is grooved or channelled to form a multiplicity of ribs 6 which are approximately T-shaped in cross-sections; that is to say, their free outer portions or cross-pieces are substantially flat and have a much greater width than their inner portions or stems, the separating spaces or channels between adjacent ribs having of necessity the reverse formation in point of cross-sectional shape and relative dimensions. 60 The outer portions of the ribs contact directly with the insulating layer 7, but because of their width they are not liable to cut into said layer if the cable should be subjected to crushing forces; and for the same 65 reason, electric stresses are avoided because the edges of the said rib portions may be, and preferably are, rounded slightly. Furthermore, the aforesaid portions are in continuous contact with, and cover substantially the 70 entire surface of, the insulation. The oil, of course, flows freely through the previously-mentioned spaces or channels between the ribs, which channels are nearly closed by the outer portions of the ribs due to their 75 peculiar formation.

I claim as my invention:—

1. A high tension electric cable, comprising conducting means, insulation surrounding the same, and a lead sheath enclosing 80 said insulation and having spaced, longitudinally-extending ribs formed on its inner surface, the free outer portions of which contact directly with the surface of the insulation and are considerably enlarged with 85 relation to their inner portions; the spaces between adjacent ribs constituting oil channels.

2. A high tension electric cable, comprising conducting means, insulation surrounding the same, and a lead sheath enclosing 90 said insulation and having spaced, longitudinally-extending ribs formed on its inner surface, the free outer portions of which contact directly with the surface of the insulation and are considerably enlarged with 95 relation to their inner portions so as to cover substantially the entire extent of said insulation surface; the spaces between adjacent 100 ribs constituting oil channels.

3. A high tension electric cable, comprising conducting means, insulation surrounding the same, and a lead sheath enclosing 105 said insulation and having spaced, longitudinally-extending ribs formed on its inner sur-

face, the free outer portions of which contact directly with the surface of the insulation and are considerably enlarged with relation to their inner portions and are rounded at their edges; the spaces between adjacent ribs constituting oil channels.

4. A high tension electric cable, according to claim 1, in which the ribs are approximately T-shaped in cross-section, the stems of the T's being integrally connected to the lead sheath.

5. A high tension electric cable, according to claim 1, in which the ribs are approximately T-shaped in cross-section, the cross-
15 pieces of the T's contacting with the surface of the insulation and having their edges

rounded, and the stems of the T's being integrally connected to the lead sheath.

6. A high tension electric cable, comprising conducting means, insulation surrounding the same, and a lead sheath enclosing said insulation and having its inner surface provided with integral, longitudinally-extending ribs which are spaced from one another to form intermediate oil passages; adjacent ribs having their free outer portions enlarged and projecting laterally toward each other so as to nearly close such passages.

In testimony whereof I affix my signature.

LUIGI EMANUELI.
